* cited by examiner

Primary Examiner — Dana L Meyrow(74) *Attorney, Agent, or Firm* — Sterne, Kessler, Goldstein & Fox P.L.L.C.(57) **CLAIM**

The ornamental design for a bottle, as shown and described.

DESCRIPTION

FIG. 1 is a top, front, right perspective view of a bottle showing the claimed design;

FIG. 2 is a front view thereof;

FIG. 3 is a right side view thereof;

FIG. 4 is a rear view thereof;

FIG. 5 is a left side view thereof; and,

FIG. 6 is a top view thereof.

The dashed broken lines in the figures show portions of the bottle that form no part of the claimed design. The dot-dash broken lines in the figures show boundaries that form no part of the claimed design.
